UNITED STATES PATENT OFFICE.

ANTOINE LACROIX, JR., OF BROOKLYN, NEW YORK.

DESIGN FOR THE EXTERIOR OF A COUNTRY HOUSE.

SPECIFICATION forming part of Design No. 19,374, dated October 22, 1889.

Application filed September 28, 1889. Serial No. 325,457. Term of patent 3½ years.

To all whom it may concern:

Be it known that I, ANTOINE LACROIX, Jr., of the city of Brooklyn, in the county of Kings and State of New York, have invented and 5 produced a new and original Design for the Exterior of a Country House, of which the following is a specification, reference being had to the accompanying drawings, forming a part thereof.

10 Figure 1 represents a perspective view of a country house showing my design. Fig. 2 represents a horizontal section or plan of the first story. Fig. 3 represents a horizontal section or plan of the second story.

15 Similar letters of reference designate corresponding parts in all the figures.

A house of this design consists of two stories, with an attic third story, with piazza in front of the first story, a balcony over the 20 piazza in the second story, and with bays, all as hereinafter more particularly described in detail with reference to the drawings.

A B C D E F designate the different portions of the front of the house. About half 25 the width of the front is flat through the three stories, as indicated at A B C. The other half of the width is of varied design through the three stories, consisting in the first story of an octagonal bay D, in the second story of 30 a rectangular bay E, which projects over the bay D, and in the third story of a gable F. From the roof of the portion C of the third

story there projects a dormer G. In front of the flat portion A of the first story is a piazza H, which is wide enough to include also a 35 portion of the bay D, and also to project outward beyond the adjacent side wall. Above this piazza, but not quite covering it, is a balcony K, and the portion of the piazza not covered by this balcony has a sloping roof J. 40 The balcony also has a sloping roof L.

That side of the house adjacent to the flat portion A B of the front has the greater portion M of its length from the back forward projecting beyond that portion N next the 45 front, as shown in all the figures. The said portion M is equal through the first and second stories, and is gabled in the third story, as shown at O in Fig. 1. The part R of the 50 attic story above N has a slight slope backward, the said sloping portion uniting with the roof S of the gable O. On the other side of the house there is an octagonal bay P in the lower story, and immediately above this bay P there is a rectangular bay Q in the sec- 55 ond story.

What I claim is—

The design for the exterior of a country house, substantially as herein shown and described.

ANTOINE LACROIX, JR.
